CLAIM

I claim the ornamental design for a laundry knob, as shown and described.

DESCRIPTION

FIG. 1 is a top perspective view of the laundry knob of the present invention;

FIG. 2 is a side elevation view of the laundry knob thereof;

FIG. 3 is a top plan view of the laundry knob thereof; and,

FIG. 4 is a bottom plan view of the laundry knob thereof. The broken lines in the figures are for contextual purposes or show the environment and form no part of the claimed design.
